PHOTOELECTRIC EXPOSURE METER

Guilbert M. Hunt, Willowick, Ohio, assignor to Daystrom,
Incorporated, Murray Hill, N. J., a corporation of New
Jersey

Application May 20, 1958, Serial No. 50,988

Term of patent 14 years

(Cl. D61—1)

Figure 1 is a front view of a photoelectric exposure meter showing my new design;

Figure 2 is a side view thereof, taken from the right side;

Figure 3 is a back view thereof; and

Figure 4 is a side view thereof taken from the left side.

The dominant features of my design reside in the portions shown in full lines.

I claim:

The ornamental design for a photoelectric exposure meter, substantially as shown and described.
